[73] Assignee: **Royal Building Systems (CDN) Limited**, Weston, Canada

[57] **CLAIM**

[**] Term: **14 Years**

The ornamental design for a corner extrusion for a building structure, as shown and described.

[21] Appl. No.: **37,894**

DESCRIPTION

[22] Filed: **Apr. 24, 1995**

FIG. 1 is a perspective view of a corner extrusion to which the design is applied and looking down from the left;

[52] U.S. Cl. **D25/122**

FIG. 2 is a top plan view of the corner extrusion;

[58] **Field of Search** D25/60, 52, 124, D25/125, 122, 136; 49/DIG. 2; 52/204.5, 204.56, 204.51, 730.3, 205, 730.1, 730.4, 730.6, 731.2, 92.2, 716.8

FIG. 3 is an elevational view of the front of the corner extrusion;

[56] **References Cited**

FIG. 4 is an elevational view of the right side of the corner extrusion;

U.S. PATENT DOCUMENTS

FIG. 5 is an elevational view of the rear of the corner extrusion; and,

D. 98,067 1/1936 Hendrickson D25/60
D. 259,364 5/1981 Poth D25/124
D. 259,811 7/1981 Guy D25/124
D. 315,027 2/1991 Abbestam et al. D25/124
D. 325,178 4/1992 Corneal D25/122
742,549 10/1903 Zeh et al. 52/731.2

FIG. 6 is an elevational view of the left side of the corner extrusion.

It is understood that the corner extrusion for a building structure shown is of indeterminate length.
